CABINET FOR A TAPE SYSTEM

Clarence F. Graser and Robert V. Jones, Poughkeepsie, N.Y., assignors to International Business Machines Corporation, New York, N.Y., a corporation of New York

Filed Mar. 19, 1964, Ser. No. 79,092

Term of patent 14 years

(Cl. D26—5)

FIG. 1

FIG. 2

FIG. 1 is a view in perspective of the front and left-hand side of our design for a cabinet for a tape system.

FIG. 2 is a view in perspective of the top, rear and right-hand side of FIG. 1.

We claim:

The ornamental design for a cabinet for a tape system, substantially as shown.
